COLLAPSIBLE BOX

William H. Inman, Newark, N. Y., assignor to
Bloomer Bros. Company, Newark, N. Y., a corporation of New York

Application February 5, 1934, Serial No. 709,830

12 Claims. (Cl. 229—41)

This invention relates to cartons or boxes formed of sheet material and has for its object to provide a novel and improved box or receptacle for holding various articles and one which can be manufactured at a relatively low cost.

A further object of the invention is to generally simplify and improve boxes of this character which are formed from blanks to afford side and bottom walls constructed to permit the box to be collapsed or folded into compact form when not in use without having to disconnect the sides or other walls of the box.

A further object of the invention is to provide an improved box of the character described having parts thereof such, for example, as a plurality of supporting and bracing members therefor so arranged as to permit the box to be readily collapsed while maintaining its sides in permanently connected relation.

A further object of the invention is to provide an improved collapsible box having an unbroken bottom wall and connected side walls, two or more of which are provided with supporting or bracing parts cut from the bottom wall whereby openings are formed therein within which said parts or portions thereof are adapted to move to facilitate collapsing of the box.

To these and other ends the invention resides in certain improvements and combinations of parts, all as will be hereinafter more fully described, the novel features being pointed out in the claims at the end of the specification.

In the drawings:

Fig. 1 is a perspective view of a box constructed in accordance with the invention;

Fig. 2 is a plan view of the blank from which the box is formed;

Fig. 3 is a fragmentary plan view showing the completed box as it appears when the side and end walls are in folded relation upon the bottom wall of the box.

Fig. 4 is a sectional view illustrating one corner of the box before moving one of the end walls thereof into position to be connected with a flap on one of the side walls;

Fig. 5 is a similar view showing the side and end walls as they appear when united one with another;

Fig. 6 is a perspective view of a modified form of box;

Fig. 7 is a plan view of the blank from which the box is formed;

Fig. 8 is a plan view of the box as viewed from the bottom thereof when in collapsed or folded position;

Fig. 9 is a transverse sectional elevation through the box shown in Fig. 8 with the cover in closed position, and

Fig. 10 is a sectional elevation through one cor-

ner of the box showing the relation of the side and bottom walls when in non-collapsed position.

The same reference numerals throughout the several views indicate the same parts.

The box comprises generally a collapsible structure formed of a one-piece blank of cardboard or other suitable material cut and scored to provide side and bottom walls, the latter being cut at its corners to afford openings therein and preferably to form legs or supporting and bracing members on the side walls, which are angularly disposed when the receptacle is in use and which fold one upon another when the side walls are folded inwardly and downwardly upon the bottom wall.

The box or receptacle shown in Fig. 1 is indicated generally at 10 in closed position, the construction of the side walls of which is best indicated by the blank shown in Fig. 2. The one-piece blank comprises generally a solid unbroken bottom wall 11 from which extends the front and rear walls 12 and 13 and the end walls 14, the rear wall having an extension 15 forming the top of the box which is preferably provided with a flap 16 for insertion within the box when closing the latter, as shown in Fig. 1.

To facilitate the forming of the box, lines of scoring are provided at 17 between the bottom wall 11 and the side walls 12, 13, and 14, and also at 18 between the rear side wall 13 and the top 15, as well as at 19 to permit the flap 16 to be hinged upon the top for insertion inside of the box as shown in Fig. 1. Furthermore the front and rear side walls 12 and 13 are scored at 20 to permit the end flaps 21 thereon to be folded inwardly into proper angular relationship with respect to said walls. Likewise the end walls 14 are scored at 22 to permit of the inward and downward folding of said walls upon the bottom of the box in a manner more fully described hereinafter.

To provide for the formation of the foldable end flaps 21 and the supporting legs for the box upon the side walls thereof certain cuts are made in the blank by the dies when operating thereon. The cuts are best indicated in Fig. 2 of the drawings, those between the flaps 21 and the end walls 14 being shown at 23. The cuts by which the intermediate legs 24 are formed are indicated at 25, Fig. 2, and the cuts by which the corner legs 26 are formed are shown at 27. The end flaps 21 have downwardly projecting extensions 21a thereon, which are hingedly connected with the corner legs 26, the latter being cut from the bottom wall of the box whereby openings 28 are afforded in said wall at the corners thereof. The lower edges 29 of the extensions are beveled or inclined relative to the bottom of the box. The extensions form bracing members for the legs 26 and the side walls 12 and 13. When the end walls 30

are folded inwardly and downwardly upon the bottom wall of the box the extensions swing freely within the openings 28, at the same time clearing said bottom wall. Furthermore the openings 28 and those formed by the cutting of the legs 24 from the bottom wall serve to admit air to the interior of the box, whereby the latter will be properly ventilated when in use.

When the blank has been cut and scored as shown in Fig. 2, glue or other suitable adhesive material is applied to the triangular end portions 14a of the walls 14, as indicated by the stippling 30 in Fig. 4, or if preferred the adhesive material may be applied to the outer faces of the flaps 21. Upon application of adhesive material to one or the other of said portions they are positioned one upon another, as indicated in Fig. 5, and permanently united, whereby the body of the box is completed and made ready for use.

However, when not in use the box can be readily folded to a flat position by pushing inwardly on the central triangular portions 14b of the end walls 14, at which time the triangular portions 14a will hinge about the score lines 22, thus drawing the front and rear side walls inwardly and permitting them to be folded downwardly upon the end walls 14, in which position the cover of the box will overlie the inwardly folded front wall 12.

When folding the box in this manner the flaps 21 and extensions 21a thereon will be permitted to move to the flat position shown in Fig. 3, without interference by the bottom wall 11, since the proper clearance for the extensions is afforded by the openings 28 formed by cutting out the material constituting the legs 26, as previously stated.

It will be noted that the end flaps 21 are permanently fixed upon the stippled portions 31 of the triangular members 14a by the adhesive material thereon, but that the lower ends of the flaps, including the extensions 21a are not glued to the central portions 14b of the end walls 14 whereby said ends will move relative to said central portions when the end walls are swung inwardly and downwardly on the bottom wall, upon collapsing or folding the box to the flat position shown in Fig. 3.

In folding or collapsing the box the flaps 21 will be swung downwardly as well as inwardly 50 but by reason of the beveled or inclined portions 29 of the flaps they are permitted to swing freely without undue interference by the bottom wall of the box.

It will be noted that the corner legs 26 of the box constitute extensions only of the front and rear walls 12 and 13 thereof and that the extensions 21a of the flaps 21 serve merely to brace the legs through cooperation with the bottom wall of the box at points adjacent the end walls 14 against the inner faces of which the flaps lie.

There is also an advantage in forming the inner end of the flap by a straight line cut since it simplifies to a certain extent the blanking operations and the construction of the dies as well and thereby reduces the cost of constructing the box.

While the receptacle shown in Figs. 1 to 5 inclusive may be readily used as an egg carton, it will be understood that it is equally useful as a container for holding various other articles and one in which the articles may be stored or shipped as desired.

When the receptacle is to be used as an egg carton it will be provided with a suitable filler for

separating the eggs, which may be of any well known design, such for example, as that indicated generally at 31 in Fig. 1.

In the modification shown in Figs. 6 to 10 inclusive, the construction is generally the same as that shown in Figs. 1 to 5 inclusive. However, the formation of the supporting members for the box, which extend from the bottom wall thereof is somewhat different.

The one-piece blank shown in Fig. 7 comprises 10 an unbroken bottom wall 30 from which extends the front and rear walls 31, 32 and the end walls 33, the rear wall having an extension 34 forming the top of the box which is preferably provided with a flap 35 for insertion within the box 15 when closing the latter as shown in Fig. 6.

Intermediate the bottom wall and the front and rear walls are relatively narrow portions 36 and intermediate the bottom wall and the end walls are similar portions 37 which, when the box is 20 completed constitute supporting means therefor projecting below the bottom wall thereof.

To facilitate folding of the blank, lines of scoring are provided at 38 and 39 on opposite sides of the portions 36 and also at 40 and 41 on 25 opposite sides of the portions 37 as shown in Fig. 7.

Additional lines of scoring are provided at 42 between the front and rear walls and the end 30 flaps 43 thereon, and also at 44 between the rear wall and the cover 34, as well as at 45 between the cover and the flap 35. Furthermore the end walls 33 are each scored along the lines 46 to permit them to be folded inwardly and downwardly upon the bottom wall as described herein- 35 after.

The end walls 33 when scored, as shown, are formed to provide triangular end portions 33a and triangular intermediate portions 33b which constitute hinged members permitting the box when 40 completed to be collapsed as shown in Fig. 8.

The end flaps 43 are provided with relatively narrow extensions 43a which are scored at 43b to permit the extensions each to be folded or doubled back upon itself to stiffen and complete 45 the same as indicated at 43c, Fig. 6. The extensions are separated from the side walls 31 and 32 by the cuts 47, Fig. 7, the folded back portions of the extensions being secured preferably by means of the adhesive material indicated by the stippling shown on the extensions in Fig. 7.

The corners of the bottom wall of the box are cut away to afford openings 48 for receiving the extensions 43c to facilitate collapsing of the box 55 in a manner more fully described hereinafter.

After the blank has been formed, suitable adhesive material is applied to the portions 36 and 37 thereof and also to portions of the triangular members 33a of the end walls as shown by the 60 stippling in Fig. 7. The blank is then folded along the lines of scoring 38, 39, 40, and 41 to position the side walls at substantially right angles to the bottom wall in the manner best indicated in Figs. 9 and 10.

In the folding operations, the parts 36 and 37 are swung outwardly on the bottom wall along the lines of scoring 39 and 40 and the side and end walls are folded upwardly along the lines of scoring 38 and 41 respectively, at which time 70 said walls and the stippled portions adjacent thereto will be united by the adhesive material applied to the stippled portions. However, if preferred, adhesive material may be applied to the walls, instead of the relatively narrow portions 75

36 and 37, the result being the same in either case. By folding or doubling back the portions 36 and 37 upon the side and end walls of the box and securing the same by adhesive material or otherwise, as preferred, supporting members 36a and 37a are formed on the side and end walls respectively, as indicated in Figs. 9 and 10, whereby the bottom wall is maintained in spaced relation to a table or other support upon which the box may be placed, thus providing a more or less yieldable bottom for supporting the eggs or other articles forming the contents of the box.

The end flaps 43 are placed inside of the portions 33a of the end walls and are secured thereto by adhesive material as previously stated, but not to the intermediate portions 33b of the end walls over which they extend and relative to which they are free to swing when folding the end walls inwardly and downwardly upon the bottom wall, as indicated in Fig. 8.

When the box is in non-collapsed position the extensions 43c on the end flaps 43 lie opposite the ends of the box supporting members 37a, as shown in Figs. 6, 9, and 10, and are preferably made to substantially abut the ends of the doubled back portions 37a as indicated at 49, whereby the extensions serve to form bracing members for the front and rear walls of the box at the corners thereof.

The extensions are also preferably made to cooperate directly with the bottom wall 30 of the box to brace the corner portions of the front and rear walls 31 and 32, through engagement of the extensions with the edge portions of the bottom at points adjacent the end walls of the box as indicated at 50 in Fig. 10.

The portions 51 of the supporting members 36a, on the front and rear walls 31 and 32 of the box, are extended substantially into abutting relation with respect to the extensions 43c of the end flaps 43, as shown in Fig. 10.

To facilitate collapsing of the box when not in use, the end flaps 43 are beveled at 52, as shown in Figs. 7 and 10, to permit them to swing inwardly and downwardly upon the bottom wall of the box when moving the hinged portions 33a and 33b to folded position. This is made necessary for the reason that the flaps not only swing inwardly, but also swing downwardly at the same time, since the front and rear sides of the box are pulled inwardly and downwardly by the folding movements of the scored end walls, thus causing the beveled portions of the flaps to approach the bottom walls when moving to folded position. In this position the inner faces of the end flaps will lie against the inner faces of the front and rear walls 31 and 32, the flaps then extending between said walls and the hinged end portions 33a of the end walls.

When the receptacle is to be used as an egg carton, it may be provided with a suitable filler for separating the eggs, a portion of which is indicated at 53, in Fig. 6.

An important feature of the invention is the provision, in each of the two designs shown, of the openings in the bottom wall of the box at the corners thereof, which are provided to permit the box to be collapsed without having to disconnect its side walls, one from another, as usually required in boxes of this type. Without the openings, indicated at 28 in Fig. 5, and at 48 in Fig. 10, the lower ends of the flaps 21 and 43, including the extensions thereon, would be obstructed by the bottom wall when attempting

to collapse the box by folding the scored ends inwardly and downwardly upon said wall, with the result that the folding or collapsing operations could not be successfully performed.

Furthermore, should the extensions be omitted, the openings would still be required, since the flaps 43 should in any event be extended substantially to the bottom of the wall of the box to stiffen and brace the foldable end walls and the side walls as well, when the box is in non-collapsed position, in which case the lower ends of the flaps will not be interfered with by the said bottom wall. This, of course, applies to the box shown in Figs. 1 to 5 inclusive, as well as to the modified form of box.

It will be understood that while I have shown the supporting members 36a and 37a of the modified design at all four sides of the box, that if preferred, they may be provided at two sides only, and further, that instead of applying the adhesive material throughout the length of said portions it may be applied at intervals thereon, or if desired, other securing means suitable for the purpose may be employed.

I claim:

1. A collapsible box of the class described formed of sheet material, comprising a bottom wall and connected side walls a plurality of which are provided with supporting portions for the box extending below the bottom wall thereof, the remaining side walls each comprising hinged portions to permit the box to be collapsed without disconnecting its sides, certain of said hinged portions having extensions projecting below the bottom of the box when it is in noncollapsed position, said bottom wall having openings formed therein adjacent the extensions, and the latter swinging within said openings when collapsing the box.

2. A collapsible box of the class described formed of sheet material, comprising a bottom wall having corner portions thereof cut away to form openings therein, and side walls on the bottom wall two of which are each provided with hinged connected end and intermediate portions, and two other side walls each having angularly disposed end flaps, portions of which are secured upon said hinged connected end portions, the lower portions of the end flaps being unconnected with said end and intermediate hinged portions and moving within said openings and relative to said intermediate hinged portions upon folding the hinged portions inwardly and downwardly upon the bottom of the box when collapsing the same.

3. A collapsible box of the class described formed of a one-piece blank to provide a bottom wall having connected side walls, two of the side walls having leg portions for supporting the box cut from said bottom wall at the corners thereof whereby openings are formed therein, and two of the side walls each having hinged portions adapted for a folding movement inwardly and downwardly upon the bottom wall, during which movement said leg portions are adapted to move within said openings.

4. A collapsible box of the class described formed of a one-piece blank to provide an unbroken bottom wall having connected side walls, two of the side walls having legs for supporting the box cut from said bottom wall at the corners thereof and affording openings in said wall, and two of the side walls being scored for folding inwardly and downwardly upon said bottom wall when collapsing the box and having end portions

extending below the bottom of the box and adapted to move within said openings when the side walls are folded inwardly and downwardly upon said bottom wall.

5. A collapsible box of the class described formed of a one-piece blank to provide an unbroken bottom wall having connected side walls, two of the side walls being scored for a folding movement inwardly and downwardly to a substantially flat position adjacent said bottom wall whereby the remaining side walls are permitted to fold inwardly and downwardly upon said scored walls, and two of the side walls having angularly disposed leg portions at each end thereof, one of each of said leg portions being cut from said bottom wall to provide an opening therein, the other of each of said leg portions moving within said openings when collapsing the box.

20. A collapsible box of the class described formed of a one-piece blank to provide an unbroken bottom wall having connected side walls, two of the side walls having supporting legs at their ends and the other side walls having extensions projecting below the bottom of the box for bracing the side walls having the legs, said legs being cut from said bottom wall at the corners thereof whereby openings are formed in said bottom wall, one of the side walls having an extension hinged thereon and forming a cover for the box, and two of the side walls being scored for a folding movement inwardly and downwardly to a substantially flat position adjacent said bottom wall whereby the remaining side walls are permitted to fold inwardly and downwardly upon said scored walls, said extensions moving within said openings when collapsing the box.

40. A collapsible box of the class described formed of a one-piece blank to provide an unbroken bottom wall having side walls thereon, two of the opposing side walls having angularly disposed end flaps and the side walls between said opposing walls each being scored to form triangular intermediate and end portions, said end portions being connected with said end flaps, two or more of the side walls having supporting members for the box extending below said bottom wall and formed by folding portions of the blank one upon another, said bottom wall having openings formed therein adjacent said supporting members, said end and intermediate triangular portions being foldable inwardly and downwardly to a substantially flat position adjacent said bottom wall whereby said opposing walls are permitted to fold inwardly and downwardly upon the triangular end portions of the scored walls, portions of said supporting members moving within said openings when collapsing the box.

60. A collapsible box of the class described, formed from a blank cut to provide a bottom wall having side walls thereon, said bottom wall having openings in its corner portions and two of the opposing side walls being provided with extended angularly disposed end flaps, the side walls between said opposing walls each being scored to form triangular end and intermediate portions, the end portions being connected with said flaps, two or more of the side walls having

supporting members for the box extending below said bottom wall and formed by folding portions of the blank one upon another, said end flaps having extensions projecting below the bottom of the box and cooperating therewith to afford bracing means for said opposing side walls, the extensions moving within said openings when collapsing the box.

5. A collapsible box of the class described, formed of sheet material comprising a bottom wall having connected side walls, a plurality of which include hingedly connected portions whereby the box is rendered collapsible without disconnecting its side walls, certain of said side walls having supporting portions for the box normally extending below the bottom wall of the box, said bottom wall having openings therein corresponding respectively to said supporting portions, said supporting portions moving within their corresponding openings to permit said side walls to fold inwardly and downwardly upon said bottom wall when collapsing the box, a plurality of said supporting portions each having an additional box supporting portion connected therewith and angularly disposed relative thereto and normally extending below the bottom of the box.

10. A collapsible box of the class described, formed of sheet material comprising a bottom wall having connected side walls, a plurality of which include hingedly connected portions whereby the box is rendered collapsible without disconnecting its side walls, certain of said side walls having supporting devices normally extending below the bottom wall of the box, a plurality of said supporting devices each including relatively movable portions angularly disposed one relative to another, said bottom wall having openings therein corresponding respectively to said last mentioned supporting devices, one of the angularly disposed portions of each of which moves relative to the other and within its corresponding opening to permit the side walls to fold inwardly and downwardly upon said bottom wall when collapsing the box.

15. A collapsible box of the class described, formed of sheet material, comprising a bottom wall having foldable side walls thereon a plurality of which each includes hingedly connected portions to permit the box to be collapsed without disconnecting its side walls, certain of said hingedly connected portions having parts thereon which move inwardly of the limits of the bottom of the box when collapsing the box, said bottom wall having openings formed therein adjacent said parts within which said parts are moved when collapsing the box whereby to permit the hinged portions to swing inwardly and downwardly upon said bottom wall.

20. A collapsible box of the class described, comprising a bottom wall having side walls foldable inwardly and downwardly thereon, certain of the side walls having parts which extend below the bottom of the box when the box is in non-collapsed position, said bottom wall having openings formed therein adjacent the side walls having said parts and the latter moving within said openings when collapsing the box.

WILLIAM H. INMAN.
